UNITED STATES PATENT OFFICE

WILLIAM EDGAR AYNGE, OF LONDON, ENGLAND, ASSIGNOR, BY MESNE ASSIGNMENTS, TO MERGENTHALER LINOTYPE COMPANY, OF BROOKLYN, NEW YORK, A CORPORATION OF NEW YORK

MAGAZINE OF TYPOGRAPHICAL LINE COMPOSING MACHINES

Application filed December 12, 1930, Serial No. 501,835, and in Great Britain August 20, 1930.

This invention relates to the magazines of typographical machines such as those known under the trade mark "linotype", and particularly to machines in which a plurality of superposed short magazine sections are adjusted relatively to the assembler and to a lesser number of stationary upper magazine sections which serve to guide the matrices from the magazine entrance to the respective channels in the short sections.

In certain of these machines the short magazines (known as side or auxiliary magazines and here, for convenience, regarded as four in number) are located at one side of the main magazines and when adjusted columnwise, two of them are brought into operative relationship with the assembler and the upper short sections, while the upper ends of the other magazines are left exposed and uncovered, either above or below, or perhaps both above and below, the short upper sections.

Owing to the fact that two of the magazines are usually much less frequently used than are the others, a considerable amount of dust is liable to enter the exposed ends and cause trouble.

The object of the present invention is to provide means which shall ensure the automatic closing of the upper ends of those of the magazines which are not for the time being required for use, this being effected during the columnwise movement of the magazines.

With said object in view, the invention provides shields which automatically cover or close the exposed upper ends of those of the magazines which for the time being are not in use.

The invention will now be more particularly described by reference to the accompanying drawings which illustrate a constructional form of the invention as embodied in a machine having four side or auxiliary magazines adapted to selectively cooperate with two upper short sections.

In the drawings:—

Figure 1 is a diagrammatic side view of the pertinent parts of a machine embodying

the improvements, the magazine column being here shown in its highest position;

Figure 2 is a view similar to Figure 1, but showing the magazine column in its lowest position, and

Figure 3 is a view, as seen from the front of the machine, showing the shields in front elevation, and with the magazines omitted.

In the constructional form here illustrated, the upper shield 1 consists of a plate which is pivotally supported, as by the reduced ends of a rod 2, fast to the shield, in lugs 3, 3^a, attached to the sides of the underlying frame 4 of the upper short magazine section 5.

When, with this arrangement, the adjustable magazine column 6 is in its lowermost position, as shown in Figure 2, the shield 1 overlies the upper part of said column, and is resiliently held in that position by a spring 7 which encircles the rod 2 and bears at its respectively opposite ends upon the said shield and the top of the short magazine section 5. By the provision of the spring 7, the upper shield 1 is free to yield and cover the open ends of the short magazine sections of the adjustable column 6, as indicated in Figure 1, when said column is raised from a lower position; and when the column is brought into its lowermost position the shield 1, by this same spring, is automatically turned down over the top of the column, as shown in Figure 2.

For facilitating the removal of the adjustable magazine sections from the machine, provision is made for readily detaching the shield 1. Such provision may be conveniently attained by securing the lug 3^a to the frame 4 with a capacity for sidewise movement out of engaging relationship with the respective end of the rod 2. For this purpose

the lug 3^a is held to the frame 4 by a screw 8 between whose head and the said lug, is interposed a compression spring 9 which normally holds the lug on the end of the rod 2, but which allows the lug to be drawn rightwards to disengage it from that rod to enable the shield 1 to be freely removed. The lug 3^a is prevented from turning on the screw 8 by dowel pins 10 fast on the lug 3^a and loosely engaging the frame 4, or vice versa. Only one

of the lugs 3, 3^a, need be thus movable, hence, the lug 3 will usually be rigidly attached to the frame 4.

The dust cover or shield 11 at the under side of the short upper sections 5, 5^a is loosely pivoted on a rod 12, extending across adjacent parts of the machine frame, and this shield, by its own weight alone, or aided by a spring, assumes a position closely overlying the upper ends of those of the movable magazines sections which, at the time, are below the upper sections 5, 5^a as is clearly evident from Figure 2. If desired, the pivot rod 12, may be removable from the machine, for enabling the shield 11 to be easily detached when it is desired to remove the magazines from the machine. To this end the rod may, as shown in the drawings, be provided with a knurled head 12^a and be threaded, as at 12^b, into one side of the frame 4.

Although the foregoing description deals mainly with the application of the invention to the side or auxiliary magazines, said invention can, with considerable advantage, be equally well applied to the main magazines, in which arrangement the lugs supporting the upper shield would be mounted on what is known as the back bracket.

Furthermore, it is to be understood that other variations or modifications can be carried out without departing from the essential features of the invention; for instance, instead of the shield 1 being acted upon by a spring, it may be relied upon to close the ends of the magazines, by its own weight or by its own weight supplemented by an additional weight.

Having described my invention, I declare that what I claim and desire to secure by Letters Patent is:—

1. In a typographical composing machine, the combination with an adjustable column of magazines, of a shield carried on a stationary part of the machine and movable automatically, by the raising of the magazine column, to cover the upper ends of those of the magazines which are brought into inoperative position by such raising.

2. In a typographical composing machine, the combination with an adjustable column of magazines, of a shield pivotally mounted on a stationary part of the machine so as to overlie the topmost magazine when the latter is in operative position, and movable on its pivot, by the raising of the magazine column, through engagement therewith to a position in which it covers the upper ends of those of the magazines which are brought into inoperative position by such raising.

3. In a typographical composing machine, the combination with an adjustable column of magazines, of a shield adapted to overlie the topmost magazine when the latter is in operative position and to cover the upper ends of magazines raised to inoperative posi-

tion, lugs on the machine frame pivotally supporting the said shield at respectively opposite sides and yielding means attaching at least one of the lugs to the machine frame with a capacity for disengagement from the shield.

4. In a typographical composing machine, the combination with an adjustable column of magazines, of a shield adapted to overlie the topmost magazine when the latter is in operative position and to cover the upper ends of magazines raised to inoperative position, a pivot for the shield, lugs on respectively opposite sides of the machine frame engaging the pivot and yielding means attaching at least one of the lugs to the machine frame to permit disengagement of the pivot therefrom.

5. In a typographical composing machine, the combination with an adjustable column of magazines and an upper shield carried on a stationary part of the machine and adapted to be moved, by the raising of the magazine column, to cover the upper ends of those of the magazines which are brought into inoperative position by such raising, of a lower shield yieldingly supported on a stationary part of the machine frame and adapted to overlie the upper ends of the magazines which are brought into inoperative position by the lowering of the magazine column.

6. In a typographical composing machine, the combination with an adjustable column of magazines and an upper shield carried on a stationary part of the machine and adapted to be moved, by the raising of the magazine column, to cover the upper ends of those of the magazines which are brought into inoperative position by such raising, of a lower shield and a disengageable pivot supporting said lower shield on a stationary part of the machine frame in a position in which said lower shield overlies the upper ends of the magazines which are brought into inoperative position by the lowering of the magazine column.

7. In a typographical composing machine, the combination of a plurality of superposed lower magazine sections, a smaller plurality of upper magazine sections relatively to which the lower magazine sections are adjustable to bring them selectively into operative register, and a shield carried on the frame of the upper magazine sections adapted to overlie the topmost lower magazine section when the latter is in operative position and to be moved thereby when the column is raised into a position in which it covers the upper ends of those magazine sections which are brought into inoperative position above the upper magazine sections.

8. In a typographical composing machine, the combination of a plurality of superposed lower magazine sections, a smaller plurality of upper magazine sections relatively to

which the lower magazine sections are adjustable to bring them selectively into operative register, and a shield pivotally mounted on the frame of the upper magazine sections and adapted to overlie the topmost lower magazine section when the latter is in operative position, said shield being movable on its pivot by the raising of the lower magazine sections to a position in which it covers the upper ends of those magazine sections which are brought into inoperative position above the upper magazine sections.

9. In a typographical composing machine, the combination of a plurality of superposed lower magazine sections, a smaller plurality of upper magazine sections relatively to which the lower magazine sections are adjustable to bring them selectively into operative register, a shield adapted to overlie the topmost lower magazine section when the latter is in operative position and to cover the upper ends of the lower magazine sections raised to inoperative position, lugs on the frame of the upper magazine sections pivotally supporting the said shield at respectively opposite sides, and yielding means attaching at least one of the lugs to the said frame with a capacity for disengagement from the shield.

30 10. In a typographical composing machine, the combination of a plurality of superposed lower magazine sections, a smaller plurality of upper magazine sections relatively to which the lower magazine sections are adjustable to bring them selectively into operative register, a shield adapted to overlie the topmost lower magazine section when the latter is in operative position and to cover the upper ends of the lower magazine sections raised to inoperative position, a pivot for the shield, lugs on respectively opposite sides of the frame of the upper magazine section engaging the pivot, and yielding means attaching at least one of the lugs to the said frame to permit disengagement of the pivot therefrom.

11. In a typographical composing machine, the combination of a plurality of superposed lower magazine sections, a smaller plurality of upper magazine sections relatively to which the lower magazine sections are adjustable to bring them selectively into operative register, an upper shield carried on the frame of the upper magazine sections adapted to overlie the topmost lower magazine section when the latter is in operative position and to be moved thereby when the column is raised into a position in which it covers the upper ends of those magazine sections which are brought into inoperative position above the upper magazine sections, and a lower shield yieldingly supported on a stationary part of the machine frame and adapted to overlie the upper ends of the lower magazine sections which are brought into inopera-

tive position below the upper magazine sections.

12. In a typographical composing machine, the combination of a plurality of superposed lower magazine sections, a smaller plurality of upper magazine sections relatively to which the lower magazine sections are adjustable to bring them selectively into operative register, an upper shield carried on the frame of the upper magazine sections adapted to overlie the topmost lower magazine section when the latter is in operative position and to be moved thereby when the column is raised into a position in which it covers the upper ends of those magazine sections which are brought into inoperative position above the upper magazine sections, a lower shield, and a disengageable pivot supporting said lower shield on a stationary part of the machine frame in a position in which said lower shield overlies the upper ends of the lower magazine sections which are brought into inoperative position below the upper magazine sections.

In witness whereof I have affixed my signature hereto.

WILLIAM EDGAR AYNGE.
